TWO-CYCLE INTERNAL COMBUSTION
ENGINEHan Lieberherr, Winterthur, Switzerland, assign-
or to Sulzer Frères, Société Anonyme, Winter-
thur, SwitzerlandApplication June 15, 1938, Serial No. 213,755
In Switzerland June 30, 1937

7 Claims. (Cl. 123—65)

The invention relates to a two-cycle internal-combustion engine having the admission ports for the scavenging and charging air arranged opposite to the exhaust ports. The invention relates particularly to two-cycle internal-combustion engines in which the admission ports open only after the exhaust ports have been opened and pressure equalization has become established in the cylinder.

5 It is known that once a jet of air is in motion it can be deflected from its path of motion by another jet of air only with an extraordinarily large expenditure of energy. In the scavenging of engines operating on the two-cycle system, the flow which is the first to be established in the cylinder predominates throughout the scavenging period. In those engines in which cross-scavenging streams of air may enter first from the middle ports, the scavenging from those ports will prevail

10 during the entire duration of the scavenging period with the air directed as a jet towards the opposite cylinder wall. The streams emerging from the lateral, rearwardly disposed ports have a small effect.

15 It is an object of the invention to so construct and arrange the engine cylinder and its associated means for the admission of scavenging and charging air (hereinafter called admitted-air) that the air is charged through the middle ports at least simultaneously with, or even slightly later than, the air charged through the other ports.

20 In accordance with invention, air control ducts of approximately equal length are provided which connect the cylinder admission ports to a source of air under pressure, with the result that the air is charged into all of the admission ports or slots in the cylinder simultaneously and with equal intensity. The admission ports are preferably divided into groups and each group is connected to a duct about equal to about the length of the other ducts. The ducts may be arranged completely within the cylinder jacket and equality of length may be attained by means of a baffle positioned in front of the admission ports which are closest to the supply of air. The ducts leading to the outermost ports may extend approximately horizontally and those to the inner ports may be slantwise disposed for the purpose of providing paths of flow for the admitted-air which are of approximately equal length.

25 The accompanying drawings illustrate more or less diagrammatically two embodiments of the invention, in which

Fig. 1 is a vertical section through a cylinder in one embodiment of the invention;

Fig. 2 is a horizontal section along line 2—2 of Fig. 1;

Fig. 3 is a vertical section through a cylinder in another embodiment of the invention, along line 3—3 of Fig. 4, and

Fig. 4 is a horizontal section along line 4—4 of Fig. 3.

30 In the construction and arrangement of apparatus illustrated in Figs. 1 and 2, the cylinder 1 is surrounded by a jacket 2, having a cylinder head 3 in which a fuel-admission valve 4 is mounted. A conduit 5 is arranged on the admission side of the cylinder for the supply of admitted-air under a suitable working pressure, and exhaust ports 6 are located on the opposite side of the cylinder and adapted to discharge into an exhaust passageway 6a which leads to an exhaust conduit (not shown). The admission side of the cylinder is provided with a plurality of spaced slots or ports in separate groups 10, 11 and 12 for the admission of air from the conduit 5.

35 In accordance with the invention the air paths leading from the conduit 5 to the ports 10, 11 and 12 are arranged in such a manner that they all have about the same length so that the air is admitted to each of the ports 10, 11 and 12 at about the same time and with equal intensity. The separate groups of ports 10, 11 and 12 connect to the conduit 5 by means of ducts 7, 8 and 9, respectively. The ducts are formed by the partition members 13 and 14, one end of each member bearing against the cylinder and the opposite ends extending into the conduit 5. The ducts 7, 8 and 9 formed by these members are of approximately equal lengths due to the form of the members and the extent to which they project into the conduit 5. The ducts leading to the outermost ports 12 may be disposed approximately horizontally or, depending on conditions, may even slope slightly upwardly, those leading to the inner ports may slant from the bottom upwardly depending upon exigencies of construction.

40 Figs. 3 and 4 illustrate a form of construction in which the ducts for the admission of air are arranged within the cylinder jacket. The air admitted to the ports 10' from the air conduit 5 is supplied through ducts 15 which are formed by the cylinder, the cylinder jacket, and a baffle 16 which may be integral with the jacket and which engages the cylinder. In this construction also, the air is admitted to all the ports simultaneously and with equal intensity.

Piston 17 is shown in the lower dead-center position in Figs. 1 and 3.

While the engine illustrated has open ducts leading directly to the air conduit without control or valve means, it is to be understood that the principles of the invention are applicable to engines in which one or more of the ducts is controlled by valve means.

I claim:

- 10 1. In a two-cycle internal-combustion engine having the admission ports in the cylinder arranged oppositely to the exhaust ports in the cylinder, the improvement which comprises a conduit for supplying air under a suitable pressure to the admission ports, ducts for supplying the ports with air from the conduit, said admission ports being divided into groups and each group being connected to one of the ducts, said ducts providing separate passageways of approximately equal length for the supply of air from the conduit to the admission ports, the ducts leading to the ports farthest from the conduit being substantially horizontal and the ducts leading to the ports nearest to the conduit being steeply inclined, whereby the air is admitted to the cylinder from all the admission ports at about the same time and with about equal intensity.
- 15 2. In a two-cycle internal-combustion engine having the admission ports in the cylinder arranged oppositely to the exhaust ports in the cylinder, the improvement which comprises conduit means for supplying air under a suitable pressure to the admission ports, a plurality of partitions of approximately equal length extending from the cylinder into the conduit means, a duct on each side of each partition of approximately equal length connecting the admission ports to the conduit means, whereby the air is admitted to the cylinder from all the admission ports at about the same time and with about equal intensity.
- 20 3. An engine according to claim 2 in which the ports are divided into groups and each group of ports is supplied with air by one of the ducts.
- 25 4. An engine according to claim 1 in which the cylinder is surrounded by a cylinder jacket, and the ducts are positioned within the cylinder jacket.

- 5 5. An engine according to claim 1 in which the duct means are formed by spaced members which extend from the cylinder to the conduit means, said spaced members being of different lengths, thereby equalizing the length of the ducts.
- 10 6. In a two-cycle internal-combustion engine having the admission ports in the cylinder arranged oppositely to the exhaust ports in the cylinder, the improvement which comprises a conduit for supplying air under a suitable pressure to the admission ports, said admission ports being divided into separate groups of ports, a duct leading from each group of ports into the conduit, all of said ducts being of approximately the same length, whereby the air is admitted to the cylinder from all the admission ports at about the same time and with about equal intensity, and a cylinder jacket surrounding the cylinder, said ducts being positioned within the jacket.

- 15 7. In a two-cycle internal-combustion engine having the admission ports in the cylinder arranged oppositely to the exhaust ports in the cylinder, the improvement which comprises a conduit for supplying air under a suitable pressure to the admission ports, a plurality of partition members extending from the cylinder into the conduit varying distances and forming ducts extending from the admission ports into the conduit that are all of approximately the same length, whereby the air is admitted to the cylinder from all of the admission ports at about the same time and with about equal intensity.
- 20 8. An engine according to claim 1 in which the cylinder is surrounded by a cylinder jacket, and the ducts are positioned within the cylinder jacket.
- 25 9. An engine according to claim 1 in which the duct means are formed by spaced members which extend from the cylinder to the conduit means, said spaced members being of different lengths, thereby equalizing the length of the ducts.
- 30 10. An engine according to claim 1 in which the cylinder is surrounded by a cylinder jacket, and the ducts are positioned within the cylinder jacket.
- 35 11. An engine according to claim 1 in which the cylinder is surrounded by a cylinder jacket, and the ducts are positioned within the cylinder jacket.

HANS LIEBERHERR. 40
